UNITED STATES PATENT OFFICE.

JOHN CLAYTON BACKUS, OF SMETHPORT, PENNSYLVANIA.

PIN-SETTER FOR BOWLING-ALLEYS.

No. 821,276.

Specification of Letters Patent.

Patented May 22, 1906.

Application filed July 24, 1905. Serial No. 271,125.

To all whom it may concern:

Be it known that I, JOHN CLAYTON BACKUS, a citizen of the United States, residing at Smethport, in the county of McKean and State of Pennsylvania, have invented certain new and useful Improvements in Pin-Setters for Bowling-Alleys, of which the following is a specification.

My present invention relates to positioning devices for pin-setters, and has special reference to the specific means for centering the pin accurately upon the appropriate place or spot it should occupy in relation to the other pins in the set upon the bed of a bowling-alley.

The means herein set forth are applicable to a number of the devices heretofore designed and patented for the purpose of positioning pins upon the bed of a bowling-alley and were partially described and illustrated in my application for United States Letters Patent for apparatus for setting pins of bowling-alleys, filed October 16, 1903, which said description and illustration were subsequently made public in Letters Patent numbered 771,963, issued to me upon said application on the 11th day of October, 1904.

One of the principal features in my means for centering the pins is the employment of the geometrical principle of determining that center by the determination of three points about that center. The result of the employment of that principle is the use of the fewest possible number of centering devices. My construction also is greatly simplified, the centering member being merely hinged to the frame of the pin-setting machine, requiring no other independent parts to direct or actuate its motion.

To attain the advantages of this principle in a simple and practical manner, my invention consists of a new and novel form and arrangement of parts, as will presently appear.

Figure 1 is a plan view showing the arrangement of my centering devices about the pin-receptacle of a pin-setting machine. Fig. 2 is a view showing a form of attachment of one of my centering members with a pin-setting machine. Fig. 3 shows how my centering members may be arranged to be operated by mere contact with the bed of a bowling-alley, although I prefer to operate them positively. Fig. 4 is a perspective view of a centering member, and Fig. 5 is a

perspective view of the means of attachment to the pin-setting machine.

A, A, and A are the three centering members utilized in my invention, which are grouped about the pin-receptacle of a pin-setting machine so as to operate radially toward the desired center for the pin at angles of substantially one hundred and twenty degrees with each other. The centering members A consist of the piece a, which contacts with the pin, the supporting-arms b, which are attached to the piece a and are provided upon their projecting ends with the notches c, and the piece d, which is screwed to the pin-setting machine and is provided with notches e, and the downwardly-projecting plate f, carrying the lugs g. The notches c of the arms b are assembled with the notches e of the piece d, and the lugs g of the plate f limit the downward swing of the arms b. The piece a has a vertically-circular motion, which may be analyzed into its vertical and lateral components. The lateral component has a direction radial to the center of the pin, and it is this motion which is utilized in centering the pin. The vertical component is of no value in centering the pin; but it is this component which is utilized in operating the centering member, as it is only necessary to impart to the centering member a relatively small vertical motion, of which there is always a great supply in machines of this order, in order to secure the lateral motion necessary. This vertical motion may be secured in two ways. The first way, which I regard as preferable, is to attach a spring h between the centering member and the pin-setting machine, which will maintain the positioning member at its highest elevation in relation to the frame of the pin-setting machine with a gentle pressure. While the centering members are in this position the pin-setting machine is brought in contact with the bed of the bowling-alley, the centering members coming not quite but nearly in contact with the bed of the alley. It will be perceived that in this manner all the wear and tear incident from the impinging of the centering members upon the alley-bed will be obviated, while at the same time the broad flat bases of the centering members being parallel to and nearly in contact with the bed of the alley are locked against displacement when the pins are thrown between them. When the pin-setting machine is

elevated from the alley-bed, the weight of the pins is quite sufficient to distend the centering members against the pull of the spring *h*, leaving the pins in the position where 5 they have been located.

The second manner of operating my centering members is to permit them to hang freely, their downward swing being only limited by the lugs *g*. With this arrangement the necessary vertical impulse is given to them when the pin-setting machine settles upon the alley-bed. When the pin-setting machine is elevated, the weight of the centering members, as well as the weight of 15 the pin, distends them, leaving the pins in position.

From the foregoing description, taken in connection with the drawings, it is evident that I provide centering devices to be used 20 in connection with pin-setting machines for bowling-alleys which are extremely simple in construction and effective in operation.

What I claim as new, and desire to secure by Letters Patent, is—

25 1. In combination with a pin-setter frame having pin-openings, pin-guides disposed radially about said pin-openings and hinged to said frame at their upper ends, lugs limiting the swing of said guides about their 30 hinges, said guides being of such length as to be operated by directly contacting the bed

of the bowling-alley to come into a fixed position between said pin-setter frame and said bowling-alley bed when same are brought adjacent to each other.

35

2. In combination with a pin-setter frame having pin-openings, the bed of a bowling-alley, three pin-guides disposed radially at angles of substantially one hundred and twenty degrees about each of said pin-openings and hinged to said frame at their upper ends, the lower unattached ends of said guides directly contacting the alley-bed and being operated thereby to slide thereon into a fixed position between said frame and said 40 45 alley-bed when the frame is brought adjacent to the alley-bed.

40

3. Centering devices to be used in connection with pin-setting machines for bowling-alleys consisting of three centering members 50 for each pin, each of said members being hinged to the pin-setting machine and of a length to directly contact with the alley-bed when in operation and in final operative position.

55

In testimony whereof I affix my signature in presence of two witnesses.

JOHN CLAYTON BACKUS.
